UNITED STATES PATENT OFFICE

CHARLES A. MOORE, OF EDINA, MINNESOTA

VENTILATING AND REFRIGERATING APPARATUS

Application filed August 15, 1924, Serial No. 732,345. Renewed September 28, 1925.

My invention relates to improvements in ventilating and refrigerating apparatus.

An object of the invention is to provide an improved apparatus of the present nature for chambers for the storage of perishable lading, said apparatus being adapted to provide for refrigerated circulation of air within a chamber, also ventilated, refrigerated circulation of air therein, or a combination of 10 the two, both conditions being brought about naturally through gravitation.

A further object of the invention is to supply an apparatus, as above, the same being equipped with a fan adapted to augment the 15 flow of air through the apparatus and thus efficiently increase its capacity in ventilating the room and circulating refrigerated air therein.

With the foregoing and other objects in 20 view, which will appear in the following description, the invention resides in the novel combination and arrangement of parts and in the details of construction hereinafter described and claimed.

25 In the drawings, Fig. 1 is an elevational view of an apparatus embodying my invention, the same being illustrated as installed in a chamber and having parts thereof broken away to disclose internal structure; Fig. 2 is a vertical central sectional view taken on the line 2—2 of Fig. 1; Fig. 3 is a plan view of the apparatus illustrated in Fig. 1 and Fig. 4 is a transverse sectional view taken on the line 4—4 of Fig. 2.

35 Referring to the drawings, it will be understood that the floor, wall and ceiling portions, indicated by the numerals 10, 11 and 12, represent a part of a structure forming a chamber A for the storage of perishable commodities. My improved appliance is installed in such a chamber in the manner shown and includes in its construction two main conduits B, C, the former, a conditioning conduit through which fresh air is admitted to the chamber A, and the latter, an exhaust conduit for discharging foul air from the chamber. The conduit B comprises a cylindrical shell 13 seated at one end thereof on the floor 10 over a drain 14 in the floor, 40 said shell being fitted at its upper end with

a cap 15. Means are provided with the wall of the shell 13 for refrigerating air therein, one form of means, as shown, residing in a pipe 16 turned coil upon coil, said pipe being adapted to contain a suitable refrigerating medium and supplied with valved inlet and outlet connections 16^a, 16^b. An ingress pipe 17, leading into the chamber A through the wall 11, communicates with the shell 13 through the cap 15. Thimbles 18 at the lower margin of the shell 13 are provided with removable caps 19, said thimbles providing for the egress of refrigerated air from the shell 13 into the lower portion of the chamber, when that is desired. The conduit C is arranged within the conduit B, axially thereof, an egress pipe 20 being extended from the lower end of said conduit, through the shell 13 and wall 11 and into the outer air. 55 60 65

A supply duct 21 and a return duct 22 are disposed horizontally along the ceiling 12 of the chamber A, the supply duct 21 being slightly lower than the return duct 22 and supplied with a port 21^a in the lower side thereof, said port 21^a reaching from end to end of said duct 21. The return duct 22 also has a port therein. This port, designated as 22^a, extends from end to end of the duct 22, and differing from the port 21^a, is formed in the upperside of said duct. Said supply 70 duct 21 is connected with the shell 13 through the medium of a feed pipe 23 rising from the lower margin of said shell and the return duct 22 is connected with the upper end of the exhaust conduit C through the drop-pipe 75 24. Two additional drop-pipes 25, 26 connect said return duct 22 with the ingress pipe 17. Within said ingress pipe 17 and intermediate of the junctions between said drop-pipes 25, 26 therewith, I place a conventional fan or 80 blower 27, the purpose of which will soon appear. The drop-pipes 24, 25 and 26 and ingress pipe 17 are respectively fitted with dampers 24^a, 25^a, 26^a and 17^a, as shown. 85 90 95

In use, a suitable refrigerating medium is circulated through the coiled pipe 16, said medium serving, primarily, to refrigerate the air within the shell 13 and, secondarily, to lower the temperature of the air within the exhaust conduit C. 100

By removing one or more of the caps 19, opening the valve 26^a and closing the valves 17^a, 24^a and 25^a, the fan 27 being idle, natural refrigerated internal circulation of air within the chamber is attained. Under this condition air within the shell 13 is chilled by the refrigerant in the pipe 16, and, thus affected, flows through the open thimble 18 into the room. Tempered in the chamber, said air rises to the ceiling and entering the port 22^a of the duct 22 returns through said duct and the drop-pipe 26 to the shell 13.

Opening the valves 17^a, 24^a results in natural mixed, refrigerated, ventilated, internal circulation. Under this condition it will be understood that fresh air is admitted to the shell 13 through the ingress pipe 17 and that a part of the air entering the return duct 22 is exhausted into the outer atmosphere through the drop-pipe 24, chilled conduit C and egress pipe 20.

Closing the valve 26^a resolves the last mentioned condition into that of natural refrigerated ventilation within the room, under which condition all of the air entering the return duct 22 is exhausted through the drop-pipe 24, conduit C and egress pipe 20.

Operation of the fan 17 augments the naturally created conditions above pointed out, and provides for supplying chilled air to the chamber A at the top thereof. Upon applying the caps 19 to the thimbles 18, air propelled downward through the shell 13 by the fan 17, is led to the supply duct 21, through the upright feed pipe 23, and directed downwardly into the chamber A through the port 21^a in the underside of said duct 21. The damper 24^a, according to the adjustment thereof, either blocks or permits of the exhaustion of air into the outer atmosphere, as before. The damper 26^a is closed and the damper 25^a opened. With said fan 17 idle there is no need of returning air past and in contact with it. Therefore, the damper 25^a is closed and the damper 26^a opened, when the appliance is operating naturally. Under force, however, and with the fan 27 rotating it is necessary to admit returning air to the pipe 17 at the suction side of the fan 27 and to block said air against "shorting" into the duct 22 through the drop-pipe 26. The valves 25^a, 26^a for this reason are adjusted as described, the former being opened and the latter closed, when the fan 27 is put to use.

While the feed pipe 23 and supply duct 21 are used in connection with the fan 27 to deliver chilled air into the upper portion of the chamber A, it will be understood that such air may be supplied to the lower portion of the chamber, under pressure of the fan, by removing one or more of the caps 19 from the thimbles 18.

Changes in the specific form of my invention, as herein disclosed, may be made within

the scope of what is claimed without departing from the spirit of my invention.

Having described my invention, what I claim as new and desire to protect by Letters Patent is:

1. The combination with a structure forming a lading chamber, of means within said chamber including an upright air conditioning conduit, an element associated with said conduit for refrigerating air therein, an upright exhaust conduit within said conditioning conduit, an elevated supply duct opening downwardly into the chamber, an elevated return duct communicating with the chamber along and near the ceiling thereof, a valved ingress pipe leading inwardly from without the chamber to the upper end of the conditioning conduit, said conduit having valved communication at the lower end thereof with the chamber near the floor, a feed pipe leading upward from said lower end of the conditioning conduit to the supply duct, a valved drop-pipe connecting the return duct with the upper end of the exhaust conduit, an egress pipe leading from the lower end of the exhaust duct to the outer air, a pair of spaced, valved drop-pipes connecting said return duct with said ingress pipe, and a fan within said ingress pipe and between the junctions of said spaced drop-pipes with said ingress pipe.

2. The combination with a structure forming a lading chamber, of means within said chamber including an upright air conditioning conduit, an element associated with said conduit for refrigerating air therein, an upright exhaust conduit in near proximity to said conditioning conduit and affected by said element, an elevated supply duct opening downwardly into the chamber, an elevated return duct communicating with the chamber along and near the ceiling thereof, an ingress pipe leading inwardly from without the chamber to the upper end of the conditioning conduit, a feed pipe leading upward from the lower end of the conditioning conduit to the supply duct, a valved drop-pipe connecting the return duct with the upper end of the exhaust conduit, an egress pipe leading from the lower end of the exhaust duct to the outer air, a fan in the ingress pipe and a valved drop-pipe connecting the return duct with said ingress pipe at the suction side of said fan.

3. The combination with a structure forming a lading chamber, of means within said chamber including an upright air conditioning conduit, an element associated with said conduit for refrigerating air therein, an upright exhaust conduit adjacent said conditioning conduit, an elevated supply duct opening into the chamber, an elevated return duct communicating with the chamber near the ceiling thereof, a valved ingress pipe leading inwardly from without the chamber to

the upper end of the conditioning conduit, a feed pipe leading upward from the lower end of the conditioning conduit to the supply duct, a valved drop-pipe connecting the return duct with the upper end of the exhaust conduit, an egress pipe leading from the lower end of the exhaust duct to the outer air, a pair of spaced, valved drop-pipes connecting said return duct with said ingress pipe, and a fan within said ingress pipe and between the junctions of said spaced drop-pipes with said ingress pipe.

4. The combination with a structure forming a lading chamber, of means within said chamber including an upright air conditioning conduit, an element associated with said conduit for refrigerating air therein, an upright exhaust conduit, an elevated supply duct opening into the chamber, an elevated return duct communicating with the chamber near the ceiling thereof, an ingress pipe leading inwardly from without the chamber to the upper end of the conditioning conduit, a feed pipe leading upward from the lower end of the conditioning conduit to the supply duct, a drop-pipe connecting the return duct with the upper end of the exhaust conduit, an egress pipe leading from the lower end of the exhaust duct to the outer air, and a fan in the ingress pipe.

5. The combination with a structure forming a lading chamber, of means within said chamber including an upright air conditioning conduit communicating at its lower end with the interior of the chamber near the floor thereof, an element associated with said conduit for refrigerating air therein, an upright exhaust conduit positioned near the air conditioning conduit and affected by said element, said exhaust conduit communicating at its lower end with the outer atmosphere, an air ingress pipe leading from without the chamber into the upper end of the conditioning conduit, an elevated, elongated duct communicating with the chamber along the ceiling thereof, a valved drop-pipe connecting said duct with the upper end of the exhaust conduit, and a second valved drop-pipe connecting said duct with the upper end of the conditioning duct.

6. The combination with a structure forming a lading chamber, of an elevated supply duct opening into the chamber, an elevated return duct communicating with the interior of the chamber near the ceiling, an upright air conditioning conduit, air refrigerating means associated therewith, said conduit communicating at its upper end with the outer air and at its lower end with said supply duct, an upright exhaust conduit communicating at its upper end with said return duct and at its lower end with the outer air, and a fan associated with said conditioning conduit for impelling air therethrough and building up an internal pressure within the room for stim-

ulating the flow of air through the exhaust conduit.

7. The combination with a structure forming a lading chamber, of an elevated supply duct opening into the chamber, an elevated return duct communicating with the chamber near the ceiling thereof, an upright conduit, a refrigerant container associated therewith for refrigerating air therein, said conduit communicating at its upper end with the outer air and at its lower end with said supply duct, an upright exhaust conduit communicating at its upper end with said return duct and at its lower end with the outer air, and a fan associated with one of said conduits for impelling air therethrough and building up a pressure within the room for stimulating the flow of air through the other conduit.

In testimony whereof, I have signed my name to this specification.
